J. A. SCHLEY,
METER BOX COVER,
APPLICATION FILED FEB. 3, 1922.

1,430,760.

Patented Oct. 3, 1922.

Inventos

UNITED STATES PATENT OFFICE.

JACK A. SCHLEY, OF DALLAS, TEXAS.

METER-BOX COVER.

Application filed February 3, 1922. Serial No. 534,000.

To all whom it may concern:

Be it known that I, JACK A. SCHLEY, a citizen of the United States, residing at Dallas, in the county of Dallas and State of Texas, have invented certain new and useful Improvements in Meter-Box Covers, of which the following is a specification.

This invention relates to new and useful improvements in meter box covers.

10 The object of the invention is to provide an improved form of cover and lock therefor. An important object of the invention is to provide a locking device of such a nature as to be readily and easily assembled 15 on the cover. A further object is to provide locking means which may be cheaply constructed and which will be of a substantial nature. One of the novel features of the invention is to employ the spring which 20 actuates the locking bolt, as a retaining element for holding the bolt in place.

A construction designed to carry out the invention will be hereinafter described together with other features of the invention.

25 The invention will be more readily understood from a reading of the following specification and by reference to the accompanying drawings, in which an example of the invention is shown and wherein:

30 Fig. 1 is an underside view of the lid,

Fig. 2 is an enlarged cross section taken on the line 2—2 of Fig. 1,

Fig. 3 is an enlarged cross sectional view on the line 3—3 of Fig. 1, and

35 Fig. 4 is an enlarged detail in section on the line 4—4 of Fig. 1.

In the drawing the numeral 10 designates a cover ring which is preferably annular and may be embedded in the upper end of 40 a plastic box 11, of suitable construction; however, it is to be understood that this ring may be attached to any kind of a meter box and is not limited to use in connection with a plastic box. The ring is 45 provided with an inclined annular shoulder 12 extending upwardly from an inwardly directed annular flange 13. A flat lid 14, having the nature of a disk is provided with a beveled annular edge 15 adapted to fit 50 the shoulder 12, so that the marginal edge of said lid may rest upon the flange 13. It will be seen that the top of the lid lies flush with the top of the ring and said lid is adequately supported so that it can 55 not be easily displaced or chip off at its edges.

On the underside of the lid, I provide near one marginal edge, an integral hook 16, which is adapted to engage under the flange 13 when the lid is swung down into 60 the ring, and thus hold that portion of the lid against upward displacement. On each side of the center of the underside of the lid is cast a depending reinforcing flange 17. These flanges are tapered off at their 65 ends and are substantially parallel. It will be seen that the lid is adequately reinforced by the flanges. A boss 21 depends from the central portion of the lid and ears 20 depend from the boss on each side thereof, whereby a recess 19 is provided between the ears.

An integral keeper 22 is cast upon the underside of the lid diametrically opposite to the hook 16. The keeper has an enlarged 75 boss 23 which co-acts with the boss 21 in forming a bearing surface for a sliding locking bolt 24. The outer end of this bolt is preferably cylindrical and passes snugly through the keeper so as to engage 80 under the flange 13 and lock the lid in place. The inner end of the bolt is confined between the ears 20 which form a guide for the same. Intermediate its ends a bolt is provided with a transverse loop 25 hav. 85 ing in plan, a substantially triangular shape and adapted to receive a suitable key, which when turned will engage the inner walls of the loop and withdraw the bolt from under the flange 13 whereby the lid is unlocked. 90

A stop lug 26 is provided on the side of the bolt at the intersection of the loop therewith so as to engage the inner side of the keeper 22 and limit the outward movement of said bolt. An eye 27 is provided at the 95 intersection of the inner side of the loop and the bolt, and is for the purpose of receiving one of the legs 28 of an expansion spring 29. The other leg 30 of said spring is passed through apertures in the 100 ears 20 under the bolt and has its end upset as is shown in Fig. 1. It will be seen that the spring leg 30 supports the bolt between the ears 20 and the leg 28 also passes under the bolt to engage the eye 27 which is 105 on the opposite side.

This construction is of particular advantage in assembling the lock as it is merely necessary to place the inner end of the bolt between the ears 20, slide the bolt forwardly 110 so that it enters the keeper 22 and then by placing the spring in position the bolt is

fastened in place. It is preferable to cast the lid of iron or other cheap metal and to cast the bolt of brass or bronze so that the latter will not rust and become difficult to operate. The bolt being cast of the aforesaid metal will be comparatively smooth and the method of assembling enables the use of a bolt upon which little or no finishing is required. In some instances it may be necessary to knock off a little flash with a file, but otherwise the bolt may be assembled just as it comes from the foundry.

10 A boss 31 is cast on the underside of the lid between the flanges 17 and conforms to 15 the general shape of the loop 25. When the bolt is extended in its locking position, the loop underlies the said boss which forms a bearing for the same. By observing Fig. 1, it will be seen that the loop extends on both 20 sides on the bolt. The said loop being either in contact or in close proximity with the boss 31, will prevent rotation of the locking bolt in case the heavier side of the loop has a tendency to swing downwardly. 25 Such a rotation is further prevented by the leg 28 of the spring 29.

Within the boss 31 a key hole 32 is formed and extends through the lid. A suitable key (not shown) may be inserted through 30 the hole 32, so that the blade of the key stands within the loop 25, and when said key is rotated, said blade will engage with the inner transverse wall of the loop 25, and slide the bolt 24 inwardly, whereby the leg 35 28 of the spring is swung inwardly and said bolt held under tension. The bolt 24 being withdrawn, the lid may be swung upwardly, the hook 16 acting as a hinge. The key thus becomes a handle for lifting the lid and said 40 lid must be returned to the ring and the key turned in the loop before it can be withdrawn. When the key is turned in the loop the leg 28 slides the bolt 24 outwardly so that it engages under the flange 13 and locks 45 the lid in position.

It is pointed out that the flanges 17 are not weakened and are free from apertures. The spring acting to hold the bolt 24 in place, is very important as it enables the

lock to be quickly assembled. The parallel 50 flanges lying on opposite sides of the bolt and spring not only adequately reinforce the lid, but protect the bolt and spring during transportation of the lids.

What I claim, is:

1. In a meter box cover, the combination of a cover ring having a seat, a lid adapted to engage in said seat, a hook formed on the underside of the lid and adapted to engage under the seat of the ring, a locking bolt disposed diametrically opposite from the hook, a keeper through which the outer end of the bolt is slid able, the outer end of said bolt projecting under the seat of the ring, a key receiving loop carried by the bolt, the lid having a guide recess receiving the inner end 65 of the bolt, a spring having one leg fastened transversely of the guide and supporting the inner end of the bolt in said guide and the other end of the spring engaged with 70 said bolt, and a boss depending from the underside of the lid immediately over the loop and provided with a key hole, the under surface of the boss being in close proximity to the upper surface of the loop. 75

2. In a meter box cover, an annular shoulder and flange cover ring, a lid fitting in the ring on the flanged portion thereof, flanges depending from the underside of the lid in spaced order, a boss depending from 80 the lid, ears on each side of the boss, a hook relatively between the flanges in position to engage under the flange of the ring, a keeper depending from the lid substantially diametrically opposite to the hook, a bolt slidingly engaging in the keeper and between the ears, said bolt being in position to engage under the flange of the ring, a key loop carried by the bolt, a boss provided with a key and depending from the lid immediately 85 over the loop, and a spring disposed between the flanges having one end engaged with the bolt and the other end passing through the ears and under the bolt for supporting the same in the recess and between said ears. 90

In testimony whereof I affix my signature.

JACK A. SCHLEY.
